UNITED STATES PATENT OFFICE

JOHN B. MASERANG, OF BELLEVILLE, ILLINOIS

FENCE CORNER BRACE

Application filed April 3, 1930. Serial No. 441,401.

This invention relates to new and useful improvements in fences, and particularly to fence posts.

One object of the invention is to provide a fence post of novel and efficient construction which is especially adapted for use in a fence corner.

Another object is to provide a post so shaped at its upper end, that a heavy hammer may be used to drive the post into the ground, without injury to the said end of the post.

Another object is to provide novel means for bracing the posts at the corner of a fence.

A further object is to so construct the bottom portion of the post that said post will not easily become loosened in the ground.

Other objects and advantages will be apparent from the following description when taken in connection with the accompanying drawing.

In the drawing:

Figure 1 is a perspective view of a fence corner, showing the use of three of the improved posts and braces.

Figure 2 is a front elevation of one of the posts.

Figure 3 is a horizontal sectional view on the line 3—3 of Figure 2.

Figure 4 is a detail perspective view of one end of one of the brace bars.

Referring particularly to the accompanying drawing, 10 represents the fence post, as a whole, such post being formed with the longitudinally extending ribs 11, forming the inside or back of the post, and the longitudinal rib 12, arranged on the outer face of the post. The upper end of the post is provided with a flat face 13, covering the area of the upper ends of the ribs 11 and a portion of the body of the post, while the upper end of the rib 12 is inclined downwardly and outwardly, as indicated at 14. This face 13 is adapted to be struck by a heavy hammer, or like tool, for driving the post into the ground, the inclined face 14 being so arranged that the

hammer will not strike the same, thereby effectively preventing mashing outwardly of the upper end of said rib, with the result that the symmetry of the upper end of the post is preserved. At the lower end of the post the ribs 11 and 12 are enlarged, and instead of having the blunt, or rounded outer edge portions as in the upper portions thereof, are provided with the sharpened edges 15, which aid in the penetration of the ground, by the post. In each of the ribs 11 there are formed the openings 16, which receive the threaded ends 17, of the braces 18. Figure 4 shows a detail of the construction of an end of one of said braces. These braces are particularly adapted for the corner of a fence, where the posts are arranged in triangular formation, the horizontal braces extending from the corner post to the two adjacent posts, while the inclined braces extend from the upper portions of the corner post to the lower portions of the other posts, as clearly seen in Figure 6, of the drawing. Each of the braces includes a channeled bar 19, having the threaded studs 17 secured thereto, said studs being disposed through the openings 16, and nuts 20 engaged thereon.

As clearly shown in Figure 1, a corner unit is formed by three posts, one for the corner, and the other two for the adjacent sides or adjoining fences, with the braces connecting the posts, and spacing them the proper distances apart, so that when setting up a fence, this corner structure can be easily and quickly driven into its proper position within the fence. The angle, in the corner of the fence, can be easily adjusted, by swinging the side posts toward or away from each other, before driving the same into the ground.

What is claimed is:

A fence corner structure comprising a corner post and the adjacent post of each of the two intersecting fences, each of the posts having longitudinal ribs having openings ad-

5 jacent their upper and lower ends, rigid horizontal braces each consisting of a channel bar having studs secured in the channels at their opposite ends, and the studs secured within certain upper openings of the corner post and said side posts, and rigid inclined braces each consisting of a channeled bar having studs secured in the channels at the opposite ends thereof with said studs secured within other 10 openings of the upper end of the corner post and in openings in the lower ends of the said side posts.

In testimony whereof, I affix my signature.

JOHN B. MASERANG.
